UNITED STATES PATENT OFFICE.

PAUL M. HOTCHKIN, OF CHICAGO, ILLINOIS.

VIBRATION-CHECK FOR VEHICLES.

No. 845,088.

Specification of Letters Patent.

Patented Feb. 26, 1907.

Application filed June 15, 1905. Serial No. 265,451.

To all whom it may concern:

Be it known that I, PAUL M. HOTCHKIN, a citizen of the United States, residing at Chicago, in the county of Cook and State of Illinois, have invented certain new and useful Improvements in Vibration-Checks for Vehicles, of which the following is a specification.

This invention relates to a device for checking the excessive vibration or oscillation of the body of a spring-supported vehicle resulting from the wheels passing over uneven places in the roadway.

The device is especially applicable to motor-vehicles which travel rapidly and in which the weight carried by the springs, together with the tension of the springs, causes continued vibrations of the vehicle-body, which jolt and shock the occupants and result in more or less injurious wear and strain on the vehicle and its attachments.

The primary purpose of my invention is to produce a comparatively inexpensive and durable device which will be of such plain construction as not to be liable to get out of order, which will be unaffected by weather conditions, which can be readily adjusted to meet various requirements in use, and which will not impair the efficiency of the vehicle-springs in the manner and to the extent that such springs are useful.

It is well known that the action of the springs of a vehicle after being depressed in returning to their normal condition or position tend to throw outwardly or upwardly the object to which they are attached with a force measured by the expansive (or contractile) capacity of the springs. The function of the springs as a cushion to relieve the occupant and vehicle from jars incident to the drop of the wheels when passing over an obstruction is desirable and should not be impaired; but the converse action, which impels the occupant upward, is undesirable, and the operation of my device is to check or neutralize this action without appreciably affecting the utility of the springs.

In the accompanying drawings I have shown a preferred adaptation of the principles of my invention in the following views:

50. Figure 1 shows my device applied to the frame and springs of a vehicle, only portions of the latter being included. Fig. 2 is an elevation of the device with a portion broken away. Fig. 3 is a view, partly in section and partly in elevation, of my device with the

cylinder-head removed and the piston shown in one position; and Fig. 4 is a view similar to Fig. 3, but shows the piston in a different position.

Referring to the details of the drawings, 1 represents a cylinder of cast metal formed with an extension 1^a at the upper side, in which there is a chamber 1^b. From one side of the chamber 1^b a passage-way 1^c leads to the interior of the cylinder, and in the bottom of the chamber is a valve-opening 1^d, which communicates with the interior of the cylinder. The upper end of the extension is closed by a screw-cap 2, which is formed with a central boss 2^a, which extends part way down into the chamber 1^b. A partition 3 extends inwardly from the wall of the cylinder at a point between the port 1^d and passage-way 1^c, said wall having formed therethrough a tapering walled valve-port 3^a and terminating near the center of the cylinder with a curved foot 3^b, the concave face of which serves as a bearing for the piston, to be described.

Arranged in the opening 1^d is a check-valve 4, which is formed with a central upwardly-extending stem 4^a, and which, together with the lug 2^a, serves as a guide for an expansion coil-spring 4^b mounted thereon. The upper end of the spring bears against the cap 2 and the lower end against the valve 4, so that the tension of the spring is normally exerted to force said valve on its seat at the opening 1^d.

A valve-plug 5 has a threaded engagement 90 with the wall of the cylinder, is formed with a tapered inner end 5^a, which fits and controls the port 3^a, and is provided at its outer end with a lock-nut 5^b. A hollow shaft 6 is arranged at the center of the cylinder and 95 extends longitudinally therein. A piston 7, preferably of the form shown, is secured on the shaft 6 by a set-screw 7^a, which also serves to secure within said shaft 6 a solid shaft 8. The outer ends of the piston are in 100 close frictional contact with the inner walls of the cylinder. The shaft 8 is suitably journaled at its inner end in the end wall of the cylinder and at its outer end in a central boss 9^c on the cylinder-head 9. Said shaft 105 also passes through a cap 9^a, which is screwed on the boss 9^c and has its outer end squared to receive one end of a rod 8^a, which is secured thereon. The opposite end of the rod 8^a is suitably pivoted on the frame 12 at a 110

point directly above the center of the vehicle-springs 13.

The cylinder-head is formed with an extension 9^b, the end of which is pivoted on a block 10, which is secured to the center of the springs by suitable clips. It will be understood that the pivotal points of the rod 8^a and extension 9^b will be in vertical alinement with the vehicle-axle. (Not shown.)

10 In the drawings I have shown the cylinder partially filled with a liquid; but in practice it will be entirely filled with a liquid of relatively great specific gravity, such as glycerin or heavy vegetable oils.

15 It will be noted that in a device constructed substantially as above described the cylinder, with its rigidly-connected head and extension 9^b and the shafts 6 8, piston 7, and rod 8^a, form, in effect, two levers having a 20 pivotal correlation, the action of which is controlled by the liquid in the cylinder as it passes from one side of the piston to the other. It will also be observed that the valve-opening 1^d is large and is controlled by 25 a check-valve, which will be easily and quickly unseated by pressure from below, while the area of the opening or port 3^a may be so reduced that the passage of the liquid therethrough will be slow. From these 30 conditions it is apparent that when the piston moves from the position shown in Fig. 3 in the direction indicated by the arrow in said figure the liquid in the path of the piston will be forced through the port 1^d and passage-way 1^c into the cylinder on the opposite side of the partition 3 and that such movement will be quick.

35 The device will be so arranged that the piston will make the movement just described when the axle drops or in the downward movement of the vehicle-body. When the piston is in the position shown in Fig. 4 and moves in the direction indicated by the arrow, the upward pressure on the check-valve will be withdrawn and the spring will 40 act to return the valve to its seat. Hence the only outlet for the liquid under pressure from the piston will be through the contracted opening around the plug 5, so that the return movement of the piston will be resisted by the liquid cushion, and thus serve to 45 check the upward movement of the vehicle frame or body, which is connected with the piston through the shafts and rod, as described. The oscillation of the piston is of 50 course controllable by the load on the check-valve and the size of the opening 3^a, both of which may be easily adjusted to suit vehicles of different weights or springs of different

55 tension, as will be readily appreciated by one skilled in the art.

Though I have shown a preferred construction of my device, I do not wish to be limited to the details of same, as various modifications may be made without departing from 60 the essential elements and principles of construction and operation.

What I claim, and desire to obtain by Letters Patent, is—

1. In a device of the character described, a 70 liquid-filled cylinder adapted to be connected with the running-gear of a vehicle and having a peripheral extension with a liquid-passage therein, a radial partition-wall in said cylinder having an opening therein, an oscillating piston mounted in said cylinder and adapted to be pivotally connected with the body of a vehicle and, with said partition, dividing the cylinder into two chambers in constant communication through said opening, 75 a valve arranged in said passage and adapted to permit the flow of liquid in one direction and an adjustable valve controlling said opening.

2. In a device of the character described, a 80 cylinder connected with the running-gear of a vehicle and having a liquid passage-way arranged therein, a partition extending partially across said cylinder and having a port 85 therein, an oscillating piston adapted to be pivotally connected with the body of a vehicle, and with said partition dividing said cylinder into two liquid-holding chambers, a yielding valve arranged in said passage-way, 90 and an adjustable valve arranged in said 95 port.

3. An automatic checking device for vehicles, comprising a liquid-filled cylinder adapted to be connected with the running-gear of a vehicle, and having an extension provided with a liquid passage-way communicating with the interior of said cylinder, a valve arranged in said passage-way, a fixed partition extending part way across said cylinder and having a port therein, an adjustable valve 100 controlling said port, an oscillating piston mounted in said cylinder and together with said partition dividing the cylinder into two 105 chambers, a shaft carrying said piston, and means adapted to pivotally connect said 110 shaft with the body of a vehicle.

In testimony whereof I affix my signature in presence of two witnesses.

PAUL M. HOTCHKIN.
